[57] CLAIM

The ornamental design for an arm for office chair, as shown and described.

DESCRIPTION

FIG. 1 is a front, perspective view of the arm for office chair in accordance with the present invention;

FIG. 2 is a front, elevational view of the arm for office chair shown in FIG. 1;

FIG. 3 is a right side, elevational view of the arm for office chair shown in FIG. 1, with the left side view being the mirror image thereof;

FIG. 4 is a top plan view of the arm for office chair shown in FIG. 1;

FIG. 5 is a bottom plan view of the arm for office chair shown in FIG. 1; and,

FIG. 6 is a rear, elevational view of the arm for office chair shown in FIG. 1.

The broken lines shown in FIG. 1 are for illustrative purposes only and form no part of the claimed design.
